UNITED STATES PATENT OFFICE

152,646

DESIGN FOR A COIN BANK

Thomas E. Orr, Lakewood, Ohio

Application May 9, 1947, Serial No. 138,933

Term of patent 14 years

(Cl. D34—11)

To all whom it may concern:

Be it known that I, Thomas E. Orr, a citizen of the United States, and a resident of Lakewood, county of Cuyahoga, State of Ohio, have invented a new, original, and ornamental Design for Coin Bank, of which the following is a specification, reference being had to the accompanying drawing, forming part thereof.

I claim:

The ornamental design for a coin bank, substantially as shown.

THOMAS E. ORR.
